UNITED STATES PATENT OFFICE.

STEPHEN B. MORSS, OF RAHWAY, NEW JERSEY.

DESIGN FOR A LAMP-WICK.

SPECIFICATION forming part of Design No. 24,944, dated December 3, 1895.

Application filed May 23, 1895. Serial No. 550,449. Term of patent 14 years.

To all whom it may concern:

Be it known that I, STEPHEN B. MORSS, a citizen of the United States, residing at Rahway, Union county, New Jersey, have invented a new and original Design for Lamp-Wicks, of which the following is a specification, reference being had to the accompanying drawing, forming part thereof, wherein the figure is a perspective view of the lamp-
o wick.

In the drawing, A represents the wick-body, of tubular form. The upper end of said body

is provided with an outwardly-extending flange *a*. Said flange is of triangular cross-section, the apex *b* of the triangle extending 15 upwardly.

I claim—

The design for a lamp wick substantially as shown and described.

STEPHEN B. MORSS.
